UNITED STATES PATENT OFFICE.

CLAUDE A. P. TURNER, OF MINNEAPOLIS, MINNESOTA.

CONCRETE DAM.

1,351,588.

Specification of Letters Patent. Patented Aug. 31, 1920.

Application filed November 23, 1918. Serial No. 263,855.

To all whom it may concern:

Be it known that I, CLAUDE A. P. TURNER, of Minneapolis, Minnesota, have invented a certain new and useful Improvement 5 in Concrete Dams, and do hereby declare that the following is a full, clear, and exact description thereof.

Heretofore such dams have been constructed upon walls supporting cylindrical arches or reinforced concrete slabs forming 10 the up and down stream faces.

In the accompanying drawings,

Figure 1 is an inclined top plan view showing one arrangement of the column, 15 looking normal to the top face;

Fig. 2 is a vertical longitudinal section thereof;

Fig. 3 is a similar top plan view of another column arrangement; and

Fig. 4 is a vertical section thereof.

Fig. 5 is a plan view of a fragment of the flat plate reinforcement, all the rods over one of the column piers for the sake of clearness being omitted except the rods 25 that form the mats over the piers, and all such mats at the other piers being omitted.

Fig. 6 is a vertical section through the slab between the piers on the line 6-6, Fig. 5.

Fig. 7 is a vertical section on the line 7-7, of Fig. 5.

My improvement embodies independent inclined column piers in place of walls heretofore used, these piers supporting a flat 35 plate face of wedge shape which increases in thickness from the top to the bottom, the relative thickness of this plate is such that the flat arch and dome resistance of the concrete is combined with the plate action 40 of the reinforcement placed therein. The reinforcement contemplated is arranged to secure imitation of mathematical flat plate action to the extent that the relative thickness of the plate to the length of span per- 45 mits.

The ratio of this thickness to the span is that of 1/6 to 1/15 as contrasted to 1/25 to 1/35 in flat plate floors for which patents heretofore have been allowed the applicant 50 and in the case of the relative thinness, arch and dome action is small. The plate or slab reinforcement is shown somewhat diagrammatically, in Figs. 5 and 6, and it comprises belts 10 of parallel rods that ex- 55 tends in two directions through the slab from

column pier to column pier, such being at right angles to each other and lapping at the piers and narrow belts 11 of parallel rods, that likewise extend at right angles, but run obliquely or diagonally, and between, but not across the column piers. All these rods are carried through the zones or regions of tension in the slab and over substantially the entire area thereof and by reason of the position and distribution of the 60 rods the imitation of the characteristic action of the mathematical flat plate is secured.

Concentric with each column pier, and in the tension zone of the slab, I place a mat 70 formed of two groups 12 of crossing rods forming rectangles that are placed with their respective diameters forty-five degrees apart and provide a supplemental framework that takes part in the circumferential 75 cantaliver action that occurs in the slab concentric with the columns.

The wedge shaped slab on the up stream face is marked S, the pier column C, these being inclined and arranged approximately 80 normal to the plate. These long inclined columns tend to bend by their own weight and to relieve them inclined struts P are disposed normal thereto to support them at intervals and the down stream spillway face 85 F is held in place and supported normal to its face by the upper extremities of these same struts P.

Where the bottom of the stream is rock, 90 suitable footing excavations are made normal to the axes of the columns. The columns are placed in parallel lines (see Fig. 1) if the rock is hard but in diagonal or staggered arrangement in soft rock to secure the greatest horizontal shearing resistance. (See Fig. 3). Where the foundation is clay, the footings are to be tied together by reinforced ties or a solid mat as the nature of the bottom may demand following the customary practice in hollow dam construction in this latter respect.

The upper face is changed in cross section from a straight outline to curved outline downwardly and thickened. This provides a convenient section for the emplacement of cut-off gates for the final closure of 105 the structure and an arch that reaches from the foundation to the first line of inclined piers and shortens the length of the up- 110 stream face.

The novelty of the structure lies in its utilization of the new principle outlined of combined dome and plate action in place of plain arch or beam operation of the upper face made possible by the form of the face and manner of support. The flat plate action is due to the nature and disposition of the reinforcement and the manner of support of the slab. Such reinforcement is in the form of mats of rods running crosswise in two or more directions with substantial uniformity of distribution circumferentially in the top of the slab about the columns and extending approximately one quarter of the slab span therefrom, the reinforcement in the bottom being distributed substantially uniformly about the diagonal center of the panel, forming a mat of a diameter of approximately half the distance between the columns about the diagonal center of the slab, the area between the columns being substantially covered by the reinforcement.

As shown best in Fig. 7, the mats formed by the groups of rods, 12, are in the upper part of the slab, and lie over the slab rods that run through the upper part of the slab at the columns, and thus reinforce the slab thereat, the slab rods and the rods, 12, thus providing the circumferentially extending reinforcement concentric with the column.

The advantage of the independent piers further lies in securing greater lateral dimensions than can be economically adopted in walls for resisting the thrust combined with the fact that the circular or octagon form may be hooped so that great compressive resistance can be developed in relatively small areas.

Because in the high dam such column piers become of great length up to 200 feet or more, it is highly important that the centering be reduced in cost and for this purpose the applicant has discovered that a skeleton reinforcement is best adapted so that the skeleton may be erected in advance of pouring the concrete and the forms be hung therefrom. The primary element of this reinforcement consists of a truss 13 longitudinally following the central plane of the column piers which is rigidly connected to the skeleton 14 of the bracing strut enabling the suspension of the column pier forms direct from the trusses and filling in the usual manner. The column truss 13, is a Warren truss, and the connection of the latter with the skeleton 14 of the bracing strut is through the intermediary of the column hoops or bands 15 to which both are riveted. The upper struts the applicant proposes to utilize for the support of the face plate forms. Thus the column piers may be built in advance of the plate which may afterward be cast following up the construction of the

piers. As shown, the flow through the spillway is controlled by a gate 16 of usual construction at the crest of the dam, adjacent which are suitable steps and platforms as usual.

What I claim and desire to secure by United States Letters Patent is:

1. In a dam, the combination of an inclined concrete slab forming the upstream face, and inclined separated, slab supporting column piers, said slab having reinforcements extending over the columns and throughout the slab, between the columns, and situated in the upper part of the slab at the columns, and in the lower part of the slab between columns, all such reinforcement being situated between the upper and lower faces of the slab, and the ratio of slab thickness to span between piers being such as to secure flat arch and flat dome action.

2. A dam having for its upstream face a pier-supported concrete slab comprising an arched portion at its bottom reaching upward from the foundation, and a flat plate portion, reaching upward from said arched portion.

3. A dam having for its upstream face a concrete slab, and having lines of column piers normal to the slab, said slab comprising an arched portion at its bottom reaching from the foundation to the first line of piers, and a flat plate portion reaching upward from said arched portion.

4. In a dam, the combination of an inclined, concrete slab forming the upstream face and having reinforcement extending over the columns and throughout the slab, between the columns, and situated in the upper part of the slab at the columns, and in the lower part of the slab between columns, all such reinforcement being situated between the upper and the lower faces of the slab, and inclined separated, slab-reinforcing column piers of concrete having skeleton reinforcement with a primary member consisting of a truss extending longitudinally of the pier.

5. A dam having for its upstream face a concrete slab and having lines of column piers normal to the slab, the lines of piers being arranged in staggered relation and said slab having reinforcement extending over the columns and throughout the slab, between the columns, and situated in the upper part of the slab at the columns, and in the lower part of the slab between columns, all such reinforcement being situated between the upper and the lower faces of the slab.

In testimony that I claim the foregoing I have hereunto set my hand.

CLAUDE A. P. TURNER.
